UNITED STATES PATENT OFFICE.

HARRIS KING HALIKMAN, OF BOSTON, MASSACHUSETTS.

DESIGN FOR A SPECTACLE DISPLAY STAND.

Application filed June 30, 1924. Serial No. 10,012. Term of patent 14 years.

To all whom it may concern:

Be it known that I, HARRIS KING HALIKMAN, a citizen of the United States, residing at Boston, in the county of Suffolk and State of Massachusetts, have invented a new, original, and ornamental Design for Spectacle Display Stand, of which the following is a specification, reference being had to the accompanying drawing, forming part thereof.

Fig. 2 is an edge view of the same.

I claim:—

The ornamental design for a spectacle display stand as shown.

In testimony whereof I have hereunto set my hand.

HARRIS KING HALIKMAN.
